CLAIM

I claim the ornamental design for a depilatory device, as shown and described.

DESCRIPTION

FIG. 1 is a front elevational view of my new design, shown without the cover for a complete disclosure of the portions under the cap;

FIG. 2 is rear elevational view thereof;

FIG. 3 is a right side elevation view thereof;

FIG. 4 is a left side elevation view thereof;

FIG. 5 is a top view thereof;

FIG. 6 is a bottom view thereof;

FIG. 7 is a rear perspective view thereof, with the cover removed; and,

FIG. 8 is a rear perspective view of the assembled design, with the cover on.
